(54) **CHURN**

(76) Inventor: **Hezekiah Roberts**

*Hegiah Roberts
Sons Patent*

The subscriber is in the below Patent and making part
of the same containing a description in the words of the said Hegiah
Roberts himself of his improvement in the Ghee

To all to whom these presents shall come. Be it known that I Hegiah Roberts of Sonoma Falls in the County of Sonoma and State of New York have invented a new and useful improvement in the construction of churns for making butter and that the following is a full and exact description thereof. Take a square box of such dimensions as will accommodate in this fit an upright moveable shaft with two wings not solid but open or of rocker work. set the above firm in a square frame with two posts rising above the above and having a pine framed across the top into which the top of the upright shaft is inserted. into one of the posts frame a round moveable piece of plank with a lever attached, around this round plank attach strong pieces of leather which wind around the upright or rocker one being to the right of the other to the left and attach them there to, so that by raising the lever the said shaft will be turned one way and by depressing the same said shaft will be turned the other way, to the end of the lever attach another moveable joint, a rod of metal or timber attached at the other end to a crank on the shaft of which this crank is a part is attached on one pinion into which a spur wheel meshes which spur wheel is moved by hand on the shaft to which the pinion is attached is a balance wheel of sufficient weight to equalize the motion, these shafts are fixed in a framework connected with the square frame above mentioned. All which are described in the drawing herewith delivered. Churns like the above have long been in use in which the break or lever was moved by hand. What I claim as my own invention & not previously known is the crank, connecting by a rod of one wheel pinion & balance wheel.
